UNITED STATES PATENT OFFICE.

WILLIAM J. BAKER, OF OSWEGO, NEW YORK, ASSIGNOR OF ONE-HALF TO LEWIS G. GRIDLEY, OF OSWEGO, NEW YORK.

HAMMER FLUE-CLEANER.

979,121.

Specification of Letters Patent. Patented Dec. 20, 1910.

Application filed May 12, 1910. Serial No. 560,867.

To all whom it may concern:

Be it known that I, WILLIAM J. BAKER, of Oswego, in the county of Oswego, in the State of New York, have invented new and useful Improvements in Hammer Flue-Cleaners, of which the following, taken in connection with the accompanying drawings, is a full, clear, and exact description.

This invention relates to certain improvements in hammer flue cleaners involving the use of a tubular frame adapted to be inserted into and through the flues of a boiler and containing a lever hammer and a revolute actuating member therefor which is actuated by suitable mechanism from one end of the tubular frame.

The primary object is to remove scale and other accumulations from the exterior surfaces of the flues by vibrating the hammer against the interior surface thereof.

Another object is to inclose the hammer within the tubular frame having an opening in one side through which the hammer may be operated and adapted to rest upon the interior of the flue to support the hammer end of the lever clear therefrom when in its retracted position, so as to render the hammering operation more effective than would be the case if the hammer end of the lever were exposed to rest directly against the interior surface of such flue.

Other objects and uses will be brought out in the following description.

In the drawings: Figure 1 is an elevation of a flue cleaner embodying the various features of my invention. Fig. 2 is a longitudinal sectional view taken on line 2—2, Fig. 1, showing a portion of a flue with scale on the exterior thereof adapted to be removed by the hammer. Fig. 3 is a side elevation of the tubular frame showing the hammer lever in the opening thereof. Figs. 4 and 5 are transverse sectional views taken respectively on lines 4—4, and 5—5, Fig. 1.

This flue cleaner comprises the tubular frame —1— having an elongated slot or opening —2— in one side for receiving and permitting the operation of a hammer lever —3— which is pivoted intermediate its ends at —4— to opposite sides of the opening —2— and is provided at one end with a hammer head —5— and at its opposite end with a bearing face —6— for engagement with a rotary actuating member —7—.

The hammer end of the lever —3— is

spring pressed radially and outwardly by a laminated spring —8— which also serves to press the opposite end of the lever or bearing —6— against the face of the actuating member —7—. This spring preferably consists of a series of flat leaves secured together at one end and to one side of the tubular frame —1— by suitable fastening means as screws or bolts —9—, Fig. 2.

The tubular frame —1— is provided with opposite end heads —10— and —11— located at opposite ends of the slot —2—, said heads being provided respectively with threaded apertures —12— and —13—, the aperture —12— serving to receive the threaded end of a tubular extension —14— of the frame, while the threaded aperture —13— in the advance end head —11— is adapted to receive the threaded end of a brush frame —15— carrying a brush —16— for cleaning the interior of the flues simultaneously with the operation of the hammer which removes the scale from the exterior of the flues.

The hammer lever —3— is substantially coextensive in length with that of the slot —2— in which it plays and is located wholly between the end heads —10— and —11—, the hammer head —5— traveling in close proximity to the head —11—, so that when the tubular frame is inserted in the flue, one or both of the end heads thereof may rest against the interior of the flue when the hammer is drawn back preparatory to striking a blow against the inner face of the flue, as —α—, thereby rendering the operation of the hammer more effective than would be the case if such hammer were allowed to rest against the interior of the flue when drawn back to its extreme position against the action of the spring —8—.

The pressure of the spring —8— is applied to the inner edge of the hammer lever —3— between the fulcrum —4— and hammer head —5— and preferably near the hammer head so as to exert as much force as possible in driving the hammer forwardly to its striking position. The opposite end of the spring is secured to the frame —1— at the rear side of the fulcrum —4—, thereby affording considerable elasticity of the free end of the spring.

The portions of the spring just in advance of the securing members —9— are passed through and guided in a lengthwise slot

—17— in a transverse partition —18— in the tubular frame —1—, the partition —18— extending between the inner face of the springs and the adjacent edge of the lever 5 near the fulcrum of the latter to stiffen the sides of the tubular frame and at the same time affording means for retaining the spring against undue lateral movement, thus relieving the strain to a certain extent upon 10 the fastening members —9—.

The front portion of one side of the frame —1— diametrically opposite to the slot or opening —2— is also provided with a lengthwise opening —19— extending from 15 a point near the fulcrum —4— of the lever to the advance end head —11— to permit play of the free end of the spring therein, particularly when the hammer end of the lever —3— is drawn back and the spring is 20 thereby retracted.

One of the objects in securing the brush —16— to the advance end head —11— is to clear away the soot and other matter from the interior of the tube and in advance of 25 the hammer head —5—, so that the latter may strike directly against the metal, thereby rendering the action of the hammer more effective in removing the scale from the outer surface of the flue. The brush, therefore, located in the manner described with 30 reference to the hammer constitutes an important coacting element of the cleaner, as otherwise the accumulated soot or other material on the interior of the flue acts as a 35 cushion for the hammer and prevents the latter effectively removing the soot without repeating the operation many times at the same point, whereas when the brush or scraper —16— is moved through the flue in 40 advance of the hammer it cleans the interior of the flue from all foreign matter and enables the hammer to come into direct contact with the metal of the flue, thereby jar- 45 ring the external scale loose with a minimum amount of hammering.

The tubular extension —14— of the frame —1— may be of any desired length and preferably consists of a common metal pipe which may be made up of one or more 50 lengths according to the length of the flue which it is desired to clean.

The actuating member —7— is made in the form of a double cam or opposite eccentricities —20— secured to or forming a part 55 of a revoluble shaft —21— which extends lengthwise through and is journaled in the tubular extension —14—, said actuating member —7— being located just at the inner end of the rear end head —10— where it 60 contacts with the bearing face —6— on the adjacent end of the hammer lever —3—.

A beveled gear —22— is secured by suitable fastening means, as a set screw —23—, to the rear end of the tubular extension —14— where it is further held against 65

lengthwise movement by a collar —24— on the extreme outer end of said extension.

A rotary yoke —25— is journaled on the outer end of the shaft —21— in close proximity to the adjacent end of the tubular extension —14—, said yoke being rotated by suitable crank arms —26— and is provided with a laterally projecting stud —27— upon which is journaled a beveled gear —28—. This gear —28— meshes with the gear —22— 70 and with an additional but somewhat smaller gear or pinion —29— which is secured to the extreme outer end of the shaft —21— in proximity to the outer end of the yoke —25—, so that the yoke is held against lengthwise 80 movement between the pinion —29— and adjacent end of the tubular extension —14—.

The crank arms —26— constitute the operating means for rotating the yoke —25— and thereby rotating the shaft —21— and 85 actuating member —7— to operate the hammer —3— against the action of the spring —8— which latter presses the hammer end of the lever with a quick blow against the interior of the flue as the ends 90 of the cam face (which terminate abruptly) leave the bearing face —6—.

The crank arms —26— are rigidly united by a handle —30— at one side of the axis of the shaft —21—, the outer crank arm 95 extending diametrically to the opposite side of the axis and is also provided with a handle —31— substantially the same distance from the axis as the handle —30—, whereby the operator may obtain a double action or 100 power in the operation of the shaft —21— and its actuating member —7—.

During the operation of the hammer on its initial entrance into the flue, the outer end of the device may be supported in any suitable manner and it is also necessary to rotate the hammer supporting frame intermittently, or whenever necessary to bring the hammer head into contact with different portions of the flue throughout its circumference, and for this purpose the tubular extension is provided with a hub —32— having radial ends —33— whereby one of the operators may turn the extension and hammer supporting frame and at the same time 115 hold the outer end of the device in operative position, so that another operator may rotate the shaft by means of the crank handles —30— and —31—.

What I claim is:

1. In a flue cleaner, a tubular frame having an opening in one side and provided with opposite end heads, a transversely-disposed partition arranged in said frame, a hammer lever fulcrumed in said frame below said partition and movable in said opening, a laminated spring arranged between said partition and the inner face of the frame and engaging the hammer end of the lever for forcing the latter outwardly 130

through said opening, means for securing one end of said laminated spring to the inner face of said frame to one side of said partition, a rotary cam for operating the lever against the action of the spring, a tubular extension secured to the rear end head of said frame, a rotary shaft passing through said extension and operatively connected to the cam, and means for rotating 5 the shaft.

2. A flue cleaner comprising a tubular frame having an opening in one side, a transversely disposed partition arranged in said frame, a lever fulcrumed in said frame and 15 arranged below the partition, a laminated

spring arranged above the partition and having one end engaging the hammer end of the lever for forcing the latter outwardly through said opening, hold-fast devices for securing one end of the spring to the inner 20 face of the frame, actuating means for operating said lever against the action of said spring, and operating means for said actuating means.

In witness whereof I have hereunto set 25 my hand on this 22nd day of March 1910.

WILLIAM J. BAKER.
